(57) **CLAIM**

The ornamental design for a frame for carrying a backpack blower, as shown and described.

DESCRIPTION

FIG. 1 is a front view of a frame for carrying a backpack blower of the present invention.

FIG. 2 is a rear view of the frame for carrying a backpack blower of FIG. 1.

FIG. 3 is a top plan view of the frame for carrying a backpack blower of FIG. 1.

FIG. 4 is a bottom view of the frame for carrying a backpack blower of FIG. 1.

FIG. 5 is a right side view of the frame for carrying a backpack blower of FIG. 1.

FIG. 6 is a left side view of the frame for carrying a backpack blower of FIG. 1.

FIG. 7 is a front perspective view of the frame for carrying a backpack blower of FIG. 1.

FIG. 8 is a rear perspective view of the frame for carrying a backpack blower of FIG. 1; and,

FIG. 9 is a reference view of the frame for carrying a backpack blower of FIG. 1 in use.

The broken line showing of the environment is for illustrative purpose only and forms no part of the claimed design.
